(57) **CLAIM**

The ornamental design for a tray for a portable air compressor, as shown and described.

DESCRIPTION

FIG. 1 is a perspective view of the tray for a portable air compressor, showing my new design, wherein a portable air compressor, which is shown in broken lines and forms no part of the claimed design, is mounted on the tray for inflating a vehicle tire, e.g., on sand;

FIG. 2 is a perspective view thereof;

FIG. 3 is a top plan view thereof;

FIG. 4 is a bottom plan view thereof;

FIG. 5 is a front elevation thereof, the rear elevation being a mirror image; and,

FIG. 6 is a left side elevation thereof, the side opposite being a mirror image.

1 Claim, 4 Drawing Sheets
